CLAIM

The ornamental design for a garment, as shown and described.

DESCRIPTION

FIG. 1 is a front view of a garment according to a first embodiment of the design;

FIG. 2 is a rear view thereof;

FIG. 3 is a right side view thereof;

FIG. 4 is a left side view thereof;

FIG. 5 is a front perspective view thereof;

FIG. 6 is a rear perspective view thereof;

FIG. 7 is a front view thereof shown in an environment of use;

FIG. 8 is a left side view thereof shown in an environment of use and with the side pocket thereof shown in an opened position;

FIG. 9 is a front view of a garment according to a second embodiment of the design;

FIG. 10 is a rear view thereof;

FIG. 11 is a right side view thereof;

FIG. 12 is a left side view thereof;

FIG. 13 is a front perspective view thereof;

FIG. 14 is a rear perspective view thereof;

FIG. 15 is a front view thereof shown in an environment of use; and,

FIG. 16 is a left side view thereof shown in an environment of use and with the side pocket thereof shown in an opened position.

The broken line showing of the feet, arms, and torso in FIGS. 7 and 15 and of the item in the side pocket of the garment in FIGS. 8 and 16 is for the purpose of illustrating portions of the environmental structure and forms no part of the claimed design.
